UNITED STATES PATENT OFFICE

ROBERT DUBOIS, OF DREUX, FRANCE

REPLACEABLE RESISTANCE

Application filed May 18, 1927, Serial No. 192,415, and in Belgium March 18, 1927.

This invention relates to replaceable resistance devices and more particularly to those of the type intended for heating purposes.

5 One of the objects of the invention is to provide a structure in which the deteriorated resistance element can be quickly and easily replaced.

Another object is to provide a structure 10 permitting the replacement to be made from the outside and without necessitating disturbance of the supporting and other associated structures.

Still further objects will appear in the 15 course of the detailed description which will now be given with reference to the accompanying drawings, in which:—

Fig. 1 is an end elevation and a half section taken on 1—1. Fig. 2 of the device;

20 Fig. 2 shows the device in a section taken on line 2—2 of Fig. 1;

Fig. 3 represents a side view of a baker's oven constructed in accordance with the invention;

25 Fig. 4 is a section taken through one of the resistance elements and showing a replacing tube in position preparatory to a replacement operation.

Referring to the various figures of the 30 drawings, there is shown the bed plate of a furnace *a*, a mass of pulverized dielectric material *b*, straight horizontal resistances *h* arranged parallel to lateral walls *c* and passing freely and with play through tubes *d* supported in end walls *e* or simply through 35 openings formed in the latter. The ends of resistances *h* extend beyond the ends of tubes *d* into niches *f* which may be closed by an appropriate cover member such as *g*. A 40 series of detachable conductors or bus-bars *i* connected to the ends of each pair of adjacent resistance elements *h* convert the latter into parts of a series resistance circuit (Fig. 2).

45 When it is desired to replace one or more of the resistance elements *h*, the corresponding end bus-bar *i* is first disconnected and a hollow tube *j* introduced into tube *d* at one end of the furnace so as to enclose the resistance wire or bar *h*. Tube *j* is then pushed

into the furnace until both its ends rest in end tubes *d* and element *h* is extracted through either end of the tube *j* or, where the element has been burned apart, through both ends of the latter. The inside of tube *j* 55 may be freed of whatever pulverized material *b* is contained therein and a new resistance wire or bar *h* inserted inside the tube. It suffices only to hold element *h* in position with an appropriate tool while extracting tube *j* endwise from the furnace to complete the replacement of a burnt out or deteriorated resistance element. Pulverized material *b*, during the extraction of tube *j*, 60 moves into the space left by the latter and supports the resistance element as it did originally. By replacing the detached bus-bar *i* in position on the new element *h* the circuit is reestablished and the apparatus is 65 able to function once more.

70 When it is desired to operate on three phase current the resistances may be arranged in three parallel planes as shown in Fig. 3 and connected to the current source in the usual way. It is, of course, to be understood, that the device is not limited to such use but may be operated with any 75 form of current.

The amount of pulverized material *b* supporting elements *h* may be varied in accordance with the amount of heat it is desired to store therein and its distance from the free surface of bed-plate *a* may be varied in accordance with the temperature gradient desired between the resistance elements and the object or material to be baked or treated 80 inside the furnace.

85 What I claim is:—

1. A device of the class described comprising in combination a pair of end supports having openings formed therein, pulverized insulating material supported between said end supports, a plurality of independent, substantially rectilinear, resistance elements 90 traversing said insulating material each passing through a pair of aligned openings in the end supports, said resistance elements having a cross section smaller than the areas of the aligned openings of the end supports 95 through which they extend and being out 100

of contact with the walls of said openings, and means for electrically connecting resistance elements issuing from adjacent openings in the end supports.

- 5 2. A device of the class described comprising a plate, a frame associated with said plate and having a series of openings therethrough, independent resistance elements passing through said openings, said resistance elements having a section sufficiently less than that of the openings through which they pass to permit their being positioned out of contact with the walls of said openings, means for electrically connecting 10 adjacent resistance element, and pulverized insulating material supporting said resistance elements in position in said frame, said pulverized insulating material being of a nature to remain pulverulent at the maximum 15 temperatures attained by said resistance elements when traversed by an electric current.
3. The method of replacing an old resistance element embedded in pulverized insulating material which comprises the steps of 20 pushing a hollow tube through said insulating material so as to enclose said old resistance element, extracting the resistance element from within the tube, placing a new resistance element inside the tube, and extracting said tube from the pulverized insulating material while maintaining the new resistance element contained therein fixed position.
4. An electric furnace comprising in combination a pair of end frames having aligned openings formed therein, a plurality of independent resistors traversing said openings, each of said resistors being of sufficiently less section than that of the 25 40 openings through which they pass to permit the insertion of a tube between the walls of said openings and the body of said resistors, means for passing a current through said resistors, and a pulverized insulating material of a nature remaining pulverulent and chemically inert at the highest temperatures attainable by said resistors when traversed by a current.

In testimony whereof I have hereunto set 50 my hand.

ROBERT DUBOIS.
